FIG. 5 is a toe end view of the FIG. 1 head;

FIG. 6 is a heel end view of the FIG. 1 head;

FIG. 7 is a bottom plan view of the FIG. 1 head;

FIG. 8 is a section in elevation on lines 8—8 of FIG. 7;

FIG. 9 is a section in elevation on lines 9—9 of FIG. 7;

FIG. 10 is a section in elevation on lines 10—10 of FIG. 8; and,

FIG. 11 is a section in elevation on lines 11—11 of FIG. 8.

FIG. 1.

FIG. 2.

FIG. 3.

FIG. 4.

FIG. 5.

FIG. 6.

FIG. 7.

FIG. 8.

FIG. 9.

FIG. 10.

FIG. 11.
